HERBERT H. STEELE, OF MARCELLUS, NEW YORK, ASSIGNEE TO THE MONARCH TYPEWRITER COMPANY, OF SYRACUSE, NEW YORK, A CORPORATION OF NEW YORK.

TYPE-WRITING MACHINE.

1,080,239.

Specification of Letters Patent.

Patented Dec. 2, 1913.

Application filed October 30, 1911. Serial No. 857,440.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

My invention relates to carbon roll devices for typewriting machines and the general object of said invention is to provide new and improved devices of the character specified and which are especially adapted for use with a continuous folded work sheet. 10 To the above and other ends my invention consists in the features of construction, combinations of devices and arrangements of parts hereinafter described and particularly pointed out in the claims.

20 In some kinds of commercial typewriting, notably in railroad billing, folded work sheets are employed to provide duplicate copies, these work sheets being in a continuous strip. For example, in billing through freight where there is an interchange between different lines of railroad, two, and in some instances three or more, duplicate freight receipts are required. Where two duplicates are required it is preferable to 25 provide a bill sheet folded in triplicate, that is, folded at its opposite side edges to provide three thicknesses or plies of paper. Said work sheet is preferably continuous, being provided in a long strip which may 30 be perforated at regular intervals in receipt lengths to facilitate the severing of the receipts after they have been written. It will be clear that it is not practicable to insert carbon roll carriers between the folds of 35 such a bill sheet and the alternative has been to interleave continuous carbon strips with the plies of the bill sheet, the carbon strips being severed with the bill sheets, thus entailing considerable loss, since instead of 40 being used repeatedly until exhausted, the carbon strips are used but once. A construction has heretofore been suggested in which bands of carbon have been arranged 45 on stationary supports extending trans-

versely between the folds of the bill sheet, but such a construction is obviously impracticable, since the carbon cannot be fed or advanced with the bill sheet and will remain practically stationary opposite the 50 printing point; besides obstructing or pre-

venting the advance of the bill sheet with which the carbon is interleaved.

My present improvements overcome the disadvantages and defects of prior constructions by providing a carbon roll arranged vertically outside of the bill sheet, in combination with a guide having a turning bar over which the carbon having been led in between the superposed work sheets or plies of paper is turned downward at 50 right angles and guided between and parallel with the superposed plies of paper over and around the platen. Preferably a restoring device is also provided which re-winds the used carbon when the paper feeding devices are released from the platen. 55

In carrying out my invention in the present instance I provide a supporting frame which is detachably mounted on the traveling carriage of the machine, said frame 75 carrying two carbon rolls provided with automatic restoring devices and associated with oppositely arranged guides comprising turning bars over which the carbon is guided inward between the folds of the bill 80 sheet which is folded in triplicate, the carbon strips being then turned at right angles above the platen and led downward between the bill folds until brought within the control of the platen and the feeding devices 85 ordinarily associated therewith. The supporting frame also carries a severing device 90 which is useful in severing the work sheets from the continuous folded strip after the data on each has been completed and after the restoring devices have rewound the carbon strips on their rolls.

In carrying out my invention in the present instance I have shown it as applied to a Monarch typewriting machine but the 95 nature of the invention is such that it may be readily adapted to other styles of writing machines.

The present embodiment of my invention will be described and explained in detail in 100 connection with the accompanying drawings, wherein—

Figure 1 is a fragmentary front elevation, partly in section, of the carriage of a Monarch typewriting machine showing the 105 invention applied thereto. Fig. 2 is a side elevation of Fig. 1, parts being omitted and parts broken away. Fig. 3 is a vertical sectional view taken on a plane represented by the broken dotted line α — α in Fig. 1 and 110

looking in the direction of the arrows at said line, Fig. 3 being drawn to a larger scale than Fig. 1. Fig. 4 is a diagrammatic view showing in side elevation the way in 5 which the folded bill sheet is guided and introduced into the machine. Fig. 5 is a longitudinal vertical sectional view of the right-hand carbon roll carrier, its mounting and associate parts. Figs. 6 and 7 are de- 10 tail views in horizontal section showing devices for limiting the automatic turning movements of the carbon roll. Fig. 8 is a diagrammatic plan view, partly in section, showing the way in which the bill and car- 15 bon sheets are guided relatively to each other. Fig. 9 is a plan view, partly in horizontal section, showing the severing blade or device and associate parts.

Referring first especially to Figs. 2 and 4, 20 the lower part of the main frame 1 of the machine is surmounted by a top plate 2 above which stationary standards 3 support fixed track ways 4 which coöperate through anti-friction balls 5 with a slide bar 6 com- 25 prised in a platen carrier or carrier which further includes end bars 7, said end bars being also connected by a cross rod or bar 8. Mounted horizontally on the carriage is a 30 rotary, cylindrical platen 9 which has connected to it at one end a line spacing ratchet wheel 10, the latter coöperating with line spacing devices (not shown) which may be actuated to turn the platen through line space distances. Coöperative with the front 35 face of the platen are printing devices of the usual Monarch style, and which comprise, as shown in Fig. 4, type bars 10^a, the type bars being pivoted on hangers 10^b that are supported on a shiftable seg- 40 ment 10^c. Each type bar is operative by a train of devices comprising a link 10^d, a sub-lever 10^e and a key lever 10^f. Paper controlling devices coöperate with the platen, said devices as shown in Fig. 3 com- 45 prising a main feed roller 11 carried by spring-pressed arms 12 pivoted at 13 on brackets 14 projecting forward from the slide bar 6. Forward of the main feed roller is a secondary feed roller 15 carried 50 by spring-pressed arms 16 also pivoted on the brackets 14. The main and secondary feed rollers coöperate with the platen through openings in a paper deflector 17 hung on a rock shaft 18 journaled on the 55 end bars 7 of the platen frame. Coöperative with the platen at its front, upper side are paper controlling devices which are mounted on the rod 8 and comprise each a forwardly extending support 19 on which 60 is mounted a pivoted spring-pressed frame 20 which supports a pin 21 carrying a pressure roll 22. Lugs 23 on the supports 19 provide bearings for a rock shaft 24 to which are secured hubs 25. Fixed thereto 65 are downwardly extending guide fingers 26

slotted to afford passages for the pressure rolls 22. The rock shaft 18 is adapted for releasing purposes by devices comprising a crank arm 27 to which is pivotally connected at 28 an arm or toggle element 29 having a finger piece 30, said arm being pivotally connected at 31 with another toggle element 32 having a fixed pivot on the platen carrier. By pulling the finger piece 30 forward the rock shaft 18 may be rocked and locked in abnormal position. When rocked forward the rock shaft coöperates through lugs 33 carried by it with pins 34 on the arms 12, this coöperation releasing or throwing off the main feed roller 11 and further operating through rollers 35 carried by the arms 12 to act on the arms 16 to release the secondary feed roller 15 and the deflector 17. The rock shaft 18 is also connected with the rock shaft 24 by devices comprising 85 crank arms 36 and 37 and a connecting link 38, the crank arm 36 being fixed to the rock shaft 18 and the crank arm 37 to the rock shaft 24, the latter being rocked oppositely from the rock shaft 18 by the connecting devices aforesaid. The rocking movement of the shaft 24 operates to release the guide fingers 26 and further to release the pressure rolls 22. The release of said pressure rolls is effected through arms 39 rigid with 95 the hubs 25 and bifurcated at their lower ends to embrace the pins 21. The paper controlling and releasing mechanism above briefly described will be found set forth in greater detail in my pending application 100 Serial No. 539,954, filed January 25th, 1910 to which reference may be had for fuller explanation.

My novel carbon roll devices are mounted on a frame which is detachably supported 105 on the traveling carriage of the machine. Said frame is shown clearly in Figs. 1 to 3 and comprises side or end plates 40 which are connected near the top and also at the middle by pairs of cross or tie rods 41, said 110 rods being threaded at their ends to accommodate nuts 42, each end having a pair of nuts, one outside and one inside of the associate end plate. Each end plate is provided near its lower end with an inwardly extending hub 43 which fits over the frame rod 8 and may be secured thereto as by a detachable pin 44. The plates 40 terminate at their lower ends in downward and rearward extensions 40^a which are provided with elongated inwardly extending hubs 45, said hubs receiving the screws 13 which screw into the brackets 14 and thus further secure the detachable frame to the platen carrier. The screws 13 are elongated and replace the pivotal supports ordinarily provided for the feed roll arms 12. Additional supporting devices are provided for the carbon roll frame, said devices comprising pairs of curved arms 46 associated with each side 125 130

plate 40, said arms being splayed at their upper ends and clamped to the outer face of the associate side plate by the lower outer nuts 42. Thence the arms 46 curve outward and downward and their lower ends are splayed or flattened, the flat ends being brought together and securely clamped against the platen frame by the screw 47 which assists to hold the rod 8 in place.

10 The supporting frame above described is comparatively light but is strong and although readily attachable to and detachable from the carriage, is, when secured in place, quite rigid on its support. In order 15 to detach or dismount said frame it is only necessary to unscrew the screws 13 and to detach the rod 8 by unscrewing the screws 47.

20 Mounted on the detachable frame comprising the end plates 40 and tie rods 41 are two carbon supply rolls, one being vertically disposed outside of each end plate at right angles to the length of the platen. The details of the right-hand supply roll and its support are illustrated in Fig. 5 and since 25 the left-hand supply roll is of like construction and mounting the following description of the right-hand roll and associate devices is to be understood as applying to both the rolls.

30 A U-shaped bracket 48 is secured by a screw 49 to the lower part of the end plate 40 and extends laterally outward therefrom, the parallel horizontal arms of said bracket providing a lower support for the carbon 35 roll. The upper support therefor is provided by a pivoted bracket 50 which, as shown in Fig. 2, is pivoted on the outer end of the rear upper tie rod 41, being confined between the plate 40 and the outside nut 42.

40 The forward portion of the bracket 50 is slotted at 51 to fit over the end portion of the forward upper tie rod 41 between the outside nut 42 associated therewith and the plate 40, and said bracket terminates in a 45 finger piece 52 by which it may be swung upward on its pivot from the Fig. 2 position wherein it is kept in place by the nuts 42. The swinging bracket 50 is provided with a lateral horizontal off-set bearing 50 plate or ear 53. A bushing 54 is secured between the arms of the lower bracket 48 and provides a bearing for a shaft 55, the lower end of said shaft being reduced at 56 to take up end thrust against the lower arm 55 of the bracket.

57 indicates a plug that is reduced to receive the lower circular flange 58 of the roll holder and has a driving fit into the lower end of a tubular core 59, the opposite 60 end whereof is provided with a plug 60 secured in place by a pin 61. The shaft 55 terminates within a bearing opening 60^a in the plug 60 and its top is provided with a slot 62 to receive a screw driver for adjusting purposes, as hereinafter described. The

lower end of the shaft is secured to the bushing 54 by a set screw 63.

The duplicating material or carbon sheet 64 is wound in a roll on a tube or core 65 of paste-board or the like which is slipped down over the tube 59 and frictionally engages therewith. The core 65 projects slightly above the top of the carbon roll and receives the hub 66 of a flange 67, the flanges 58 and 67 constituting spool heads and being spaced apart by the core 65 far enough to provide clearance for the carbon roll 64. The upper flange 67 is clamped in place by a shouldered thumb screw 68, the shouldered portion 68^a thereof bearing rotatably in an opening in the stationary bearing plate 53 and also engaging clamp-wise with the top of the flange 67, said thumb screw passing through the hub 66 and its lower end being threaded into the plug 60, 35 the upper end of the opening 60^a thereof being tapped for the purpose. By screwing down the thumb screw 68, the core 65 is pressed or clamped between the two flanges or heads 67 and 58 and becomes rigid therewith and with the inner core 59 so that the carbon roll can turn to unwind the carbon only when the carbon holder or carrier rotates as a whole, said holder comprising the cores 59 and 65, the flanges 58 and 67, the 40 plugs 57 and 60 and the thumb screw 68. It will be understood that when the thumb screw 68 is removed the bracket or lever 50 may be swung up and the carbon roll, together with the outer core 65, readily removed from the machine. The shaft 55 is held from turning by the set screw 63, and a collar 69 is pinned or otherwise secured to the shaft above the plug or bushing 57 to prevent vertical displacement of the carbon roll holder while at the same time permitting rotation thereof on the shaft as a stationary axis. Coiled around the shaft 55 within the inner core 59 is a closely wound spring 70 having its lower end secured to the shaft and its upper end engaging in a vertical opening 71 in the plug or bushing 60. The tendency of the spring is constantly to turn the carbon roll holder oppositely from the direction in which it rotates when the carbon is being drawn off and fed around the platen; that is to say, the advance or delivery movement of the carbon winds the spring 70. To vary the initial tension of said spring the set screw 63 may be loosened, the thumb screw 68 removed and a screw driver inserted downward through the opening 60^a to turn the shaft 55 to wind or unwind the spring to the required tension, after which the screw 63 may be tightened to lock the shaft. Since the spring 70 is always under tension it is necessary to provide stop devices to limit the winding-up operation of the roll when the 45 advance end of the carbon paper is released 120

or freed. For this purpose the lower portion or flange of the plug or bushing 57 is formed with a single tooth 72, best shown in Figs. 6 and 7, said tooth being adapted to engage normally in a depression 73 formed in the periphery of a broad tooth 74 on a gear 75 which is further provided with a plurality of narrower teeth 76, said teeth being spaced apart to provide openings 77 in which the tooth 72 may engage. As herein shown, there are eight teeth 76. The gear wheel 75 rests on the top of the upper arm of the bracket 48 and bears on a shouldered screw 78 which, as shown in Fig. 5, is secured to said upper arm by a nut 79. Preferably the gear wheel or toothed disk 75 is so mounted as to develop sufficient friction against its support to prevent accidental or too free rotation. The normal or initial position of the toothed members or stop devices 75 and 57, 72 is shown in Fig. 6. It will be understood that the tension of the spring 70 tends to turn the tooth 72 in the direction of the arrow in Fig. 6 but rotation is prevented by the tooth 72 engaging with the depression 73 and interlocking with the gear wheel 75. When the carbon paper 64 is drawn from the roll the tooth 72 will be rotated oppositely from the arrow in Fig. 6 and after it has nearly completed a revolution will engage with the upper side of the broad tooth 74 and will turn the latter downward far enough to enable the tooth 72 to clear it. This turning movement will bring into the path of the tooth 72 the first of the narrow teeth 76 that is above the broad tooth 74 so that during the next revolution of the tooth 72 it will engage said narrow tooth and turn the gear wheel 75 through another step. This progressive or step-by-step turning operation of the gear wheel 75 by the tooth 72 will continue until the broad tooth 74 nearly completes a revolution and is brought to the position shown in Fig. 7. In this position it prevents further rotation of the tooth 72 in the direction of the arrow in Fig. 7, said tooth being locked by engagement with the depression 73 and thus locking the carbon roll against further unwinding rotation. Thus it will be seen that the carbon roll may turn through substantially nine complete revolutions from its initial position before it will be locked against further unwinding movement. The number of revolutions will depend on the number of the teeth on the gear wheel 75 and this may, of course, be varied to suit the occasion; but it will be found that nine revolutions are sufficient to permit the advance of all the carbon that is necessary for the printing of a freight bill even when the diameter of the carbon roll has been reduced to the limit.

As shown in Fig. 8 the two carbon sheets 64 are drawn off from the back of their re-

spective rolls, passing inward toward each other and toward the middle of the machine through vertical slots 80 in the end plates 40 of the supporting frame, the right-hand carbon paper passing over a guiding device 70 81 and the left-hand carbon paper over a guiding device 82. These guiding devices are between the roll holders and oppositely disposed and parallel, being preferably made of sheet metal and provided with flanges 75 which are riveted as at 83 or otherwise secured to the inner faces of the end plates 40 back of the slots 80. The guiding devices 81 and 82 are preferably made of sheet metal and may be cut out as shown in Fig. 1 to 80 reduce weight. Said devices are triangular in shape, the device 81 having its upper edge inclined downward and leftward to provide a turning bar 84, the device 82 being provided with an oppositely inclined 85 turning bar 85. The device 81 terminates at its lower left-hand edge in a tongue or finger portion 86 while the device 82 is provided at its right-hand end in a corresponding tongue 87, said tongues acting to guide the work 90 sheets and reproducing strips into the control of the platen and its paper feeding devices at the rear side thereof. The hubs 43 are flattened so as not to interfere with the guiding tongues 86 and 87. As clearly shown 95 in Fig. 1 the carbon paper or duplicating material is drawn off the carbon roll horizontally inward toward the middle of the machine and over the front of the associate guiding device and then is deflected downward at right angles over the turning bar, passing behind the same and being directed thereby toward the platen at its introductory side. The two carbon sheets are thus guided close together and downward, behind their 100 respective turning bars. Said sheets are brought within the control of the main feed roll preferably before the thumb screws 68 are tightened, the consequence being that thereafter when the carbon rolls are turned 110 against their respective springs to unwind the carbon sheets and said sheets are thereafter released from the paper feeding devices, they will be restored by the springs 70 and then arrested by the stops 72 and 75 so 115 that the lower ends of said sheets are slightly below the place at which the main feed roller 11 engages the platen.

As heretofore stated the present form of my invention is adapted to a bill sheet folded 120 in triplicate. Such bill sheet is illustrated in Figs. 4 and 8. In Fig. 8 which diagrammatically illustrates the folds of the bill sheet as interleaved with the carbon sheets 64, the bill sheet is shown as comprising a 125 rear ply 88, a middle ply 89 and a front ply 90, the rear and middle plies being joined at their right-hand edges by a bight or fold 91 and the middle and front plies being joined at the left by a fold 92. Referring to Fig. 4, 130

the continuous triplicate bill sheet or manifold paper strip is also preferably folded transversely, as indicated at 93; thus providing three-ply lengths 94 equal to the length 5 of the freight bills, these lengths usually containing printed forms. It will be understood that the transverse folds 93 include the three plies extending lengthwise of the bill sheet, although it has not been thought necessary to illustrate the three plies in Fig. 4. Of course, the manifold work sheets may be three separate superposed continuous strips instead of three connected strips but the connected form is preferable. Thus folded 10 transversely the continuous manifold sheet is placed in a receptacle 95 behind the typewriting machine, passing upward behind said machine and over a suspended guide roller 96 and thence downward to the machine, passing over the guiding devices 81 and 82, said guiding devices separating the plies of the sheet as clearly appears from Fig. 8. Referring to this figure it will be noted that the rear ply 88 passes downward 15 behind the guide 82 and that interposed between the back of said guide and the front of said ply is the vertical portion of the left-hand carbon sheet 64, the same being indicated by a dotted line. The middle ply 89 passes downward between the two guides 81 and 82, the vertical portion of the right-hand carbon strip 64 being interposed between the front face of said ply 89 and the rear face of the guide 82. The forward ply 90 of the 20 work sheet passes downward in front of and over the guide 81. The guides, it will be seen, first direct the carbon paper inward transversely of the work sheets and then downward lengthwise thereof and interlaved between the longitudinally extending plies or folds of the bill sheet. Thus the work sheets as brought within the control of the platen feeding devices comprise five 25 thicknesses superposed one on the other, three work sheets and two carbon or reproducing sheets, the work sheets and reproducing sheets alternating, the outer work sheet or ply being adapted to receive the type impressions from the regular ribbon of the 30 machine, the middle ply receiving impressions from the front carbon strip and the rear ply or work sheet receiving impressions from the rear carbon strip. In order that the carbon strip may coöperate with the 35 proper plies the carbon is wound in rolls with the carboned face outward. Provision is thus made for manifolding three copies at a single printing operation.

It will be understood that when the work 40 sheets have been brought within the control of the main feed roller, subsequent rotary movements of the platen will advance the thicknesses or plies together, the work sheet being drawn up from the receptacle 95 and 45 downward over the guide 96 and the carbon being drawn off from the supply rolls and inward and then at right angles downward over the guiding devices or turning bars. After a freight bill has been completed and it is desired to restore or retract the carbon 50 paper so that the used portion may be again employed for reproducing copies of the next following bill, the finger piece 30 may be pulled forward, releasing the various paper feeding devices as hereinbefore explained and permitting the restoring springs 70 to retract the carbon paper. During this operation the work sheet may be held by its outer flap or otherwise to prevent any friction from the backward moving carbon paper from retracting said work sheet. During the turning movements of the carbon paper the stop or tooth 72 will rotate backward, co-acting with the teeth 76 of the toothed stop gear 75, turning said gear backward also; and this backward movement of the stop devices 72 and 75 will continue until they reach the locking position shown in Fig. 6, thus locking the carbon roll from further backward turning 55 and this may be accomplished by severing devices comprising a U-shaped plate composed of side arms 97 and a narrow connecting cross bar 98, the side arms having downwardly extending ears 99 which are secured by screws 100 to the outer faces of the end plates 40. The forward portions of the plate-like side arms are curled to embrace pivot pins 101, said pins projecting inward beyond said side arms and providing bearings for a pivoted severing blade 102 having a forwardly extending finger piece 103 and a beveled rear edge 104, the forward edge of the cross bar 98 being beveled to correspond thereto. The pivoted device is maintained in the normal position 60 shown in Figs. 3 and 9 by a spring 105; and at this time the cross bar 98 and the cutting edge 104 are separated so as to provide a slot-way 106 through which the work sheet is adapted to be fed, said work sheet passing upward behind the paper fingers 26 and forward of an inclined guide plate 107 which is secured to the side arms 97. When it is desired to sever one of the work sheet sections the finger piece 103 is raised, causing the beveled edge 104 to coöperate with the forward edge of the bar 98 to clamp the work sheet therebetween. While thus holding the work sheet clamped it may be torn off by drawing it forward against the sharp 65 edge 104 of the blade 102. Thus the devices 98 and 102 coöperate both as clamping bars to clamp paper and as cutting bars to sever the same while clamped. It will be understood that when the work sheets are thus 70

severed, each section 94 comprises three plies 88, 89 and 90, containing identical entries, said plies being connected at their opposite side edges by the longitudinal folds 5 or bights 91 and 92. Consequently after the triplicate or three-ply work sheet section has been written and severed from the continuous strip, it is torn into three parts, thus providing two duplicates besides the original. When the advanced portion of the carbon paper becomes exhausted it may be severed from the strips and then the thumb screws 68 may be loosened to permit fresh portions of carbon to be unwound from the 15 rolls 64.

My present invention provides a practicable device which may be readily attached to existing styles of writing machines and affords means of economically duplicating or manifolding on continuous work sheets, even when the said sheets are folded, thus adding to the difficulties of handling the carbons or duplicating sheets, it being of course desirable in the interest of economy 20 to repeatedly use the carbons until they are exhausted.

Various changes may be made without departing from the spirit of my invention.

What I claim as new and desire to secure 30 by Letters Patent, is:—

1. In a typewriting machine, the combination of a platen, a line spacing wheel connected therewith, paper feeding devices cooperative with the surface of the platen to feed paper around the same when said line spacing wheel is actuated, a roll of reproducing material arranged at right angles to the platen, and means for guiding said material from said roll to said platen in an unvarying path, said paper feeding devices operating to feed said material around said platen when it is turned.

2. In a typewriting machine, the combination of a platen, a line spacing wheel connected therewith, paper feeding devices cooperative with the surface of the platen to feed paper around the same when said line spacing wheel is actuated, a carbon roll at right angles to the platen, and means for 45 guiding carbon paper inward from said roll and downward to said platen in an unvarying path, said paper feeding devices operating to feed said carbon paper around said platen.

3. In a typewriting machine, the combination with a platen carrier, a platen thereon, a line spacing wheel connected to said platen, paper feeding devices coöperating with the surface of the platen to feed paper 50 thereover when said line spacing wheel is turned, a roll holder mounted on said platen carrier at right angles to said platen, and means for guiding the material from said roll holder to the platen, said means having

a constant relationship with both said platen 65 and with said roll holder, said paper feeding devices operating to feed said material around said platen.

4. In a typewriting machine, the combination of a platen carrier, a platen thereon, a vertical roll holder mounted on said platen carrier at right angles to said platen, means for guiding the material from the roll holder to the platen, said means comprising a turning bar supported on the platen carrier, and means coöperating with said platen to advance said material thereover.

5. In a typewriting machine, the combination of a platen, a guiding device interposed between two superposed work sheets, and a roll holder located at one side of and clear of the path of said work sheets, the material from said work holder being led therefrom over said guide and between said work sheets, and common means for feeding said superposed work sheets and said material.

6. In a typewriting machine, the combination of a platen, a platen carrier on which the platen is horizontally mounted, a detachable frame on said platen carrier, a vertical carbon roll holder on said frame, a guiding device on said frame for changing the course of the paper and guiding it from said roll holder to said platen, and means coöperative with said platen to advance said material 95 thereover.

7. In a typewriting machine, the combination of a platen carrier, a horizontal platen supported thereon, a carbon roll holder vertically supported on said platen carrier, and a paper guide mounted on said platen carrier and arranged at an angle both to said platen and to said roll holder, said guide being interposed between the sheets of a manifold paper strip, said roll holder being arranged outside said paper strip and the carbon paper being led from said roll holder over said guide and between said sheets, the course or direction of the carbon paper being changed by said guide which directs said 105 carbon paper over said platen.

8. In a typewriting machine, the combination of a platen, a turning bar interposed between the sheets of a manifold paper strip, and a roll holder located outside the side 115 edges of said manifold strip and carrying a roll of reproducing material, said material being led from said holder to the turning bar transversely of the manifold strip and thence at right angles and lengthwise of the 120 manifold strip.

9. In a typewriting machine, the combination of a platen carrier, a platen thereon, a turning bar located on said platen carrier and interposed between continuous superposed work sheets, and a carbon roll holder located on said platen carrier outside the side edges of said work sheets, the carbon 125

paper being led from said roll holder over said turning bar and thence at right angles between said work sheets.

10. In a typewriting machine, the combination of a platen carrier, a platen thereon, vertical parallel roll holders mounted on said platen carrier at right angles to said platen and spaced apart so that work sheets may pass to the platen downward between said roll holders, and means for guiding the material from said roll holders to the platen and between a plurality of superposed sheets of paper to be written on, said means being arranged between said superposed work sheets and effecting a change in the general direction followed by said material in its course from said roll holders to said platen.

11. In a typewriting machine, the combination of a platen carrier, a platen thereon, vertical parallel roll holders mounted on said platen carrier at right angles to said platen and so that work sheets may pass to the platen downward between said roll holders, and oppositely disposed turning bars, said turning bars being at angles both to the roll holders and the platen, and guiding the material from said roll holders to the platen and between a plurality of superposed sheets of paper to be written on, said sheets being separated by said turning bars.

12. In a typewriting machine, the combination of a platen, a plurality of paper guides interposed between the sheets of a manifold paper strip, and a plurality of roll holders located outside the path of said paper strip and each supporting separate material, the material from said roll holders being led therefrom over said guides.

13. In a typewriting machine, the combination of a platen, a plurality of turning bars each interposed between two plies of a manifold paper strip, and a plurality of roll holders each located at one side of said manifold strip and carrying a roll of reproducing material, the turning bars arranged between the roll holders, said material being guided from said holders to the turning bars transversely of the manifold strip and thence at right angles lengthwise of the manifold strip and between the plies thereof.

14. In a typewriting machine, the combination of a platen carrier, a platen thereon, a plurality of turning bars on said platen carrier, each interposed between two continuous superposed printing surfaces, carbon roll holders located on the platen carrier and spaced apart lengthwise of the platen, said holders being at opposite sides of the continuous superposed printing surfaces, the carbon paper being guided from said roll holders inward over said turning bars and thence downward at right angles between said printing surfaces.

15. In a typewriting machine, the combination of a platen carrier, a platen thereon, releasable paper feeding devices extending longitudinally of the platen and coöperative therewith, a vertical roll holder mounted on said platen carrier at right angles to said platen and to the paper feeding devices, guiding means coöperative with the material from said roll holder, said guiding means changing the course of the material after it leaves said roll holder and directing said material into coöperation with said paper feeding devices, and means for turning said roll holder to rewind said material when said paper feeding devices are released.

16. In a typewriting machine, the combination of a platen, a platen carrier on which said platen is horizontally disposed, paper feeding devices extending horizontally along said platen and coöperative therewith, a detachable frame on said platen carrier, a vertical carbon roll holder on said frame, a guiding device which coöperates with the carbon paper as it leaves said holder horizontally, said guiding device guiding the paper vertically downward into the control of said paper feeding devices, and automatic means for rewinding said material from said roll holder when said paper feeding devices are released.

17. In a typewriting machine, the combination of a platen, paper feeding devices coöperative therewith, a turning bar interposed between the sheets of the manifold paper strip, a roll holder located outside the side edges of said manifold strip and carrying a roll of reproducing material, said material being guided from said holder to the turning bar transversely of the manifold strip and thence at right angles lengthwise of said strip and between the sheets thereof, and automatic means for turning said roll holder to rewind said material thereon independently of the manifold strip when the paper feeding devices are released from the platen.

18. In a typewriting machine, the combination of a platen carrier, a platen thereon, parallel roll holders mounted on said platen carrier at right angles to said platen and so that work sheets may pass to the platen downward between said roll holders, oppositely disposed turning bars, said turning bars being at angles both to the roll holders and guiding the material from said roll holders to the platen and between a plurality of superposed sheets of paper to be written on, releasable paper feeding devices coöperative with the platen, and automatic turning means for rewinding the material on said roll holders independently of the work sheets when the paper feeding devices are released from the platen.

19. In a typewriting machine, the combi-

- nation of a platen, releasable paper feeding devices co-operative therewith, a material carrying roll holder, the material wherefrom is controlled by the platen and its 5 paper feeding devices, means tending constantly to turn said roll holder in one direction, and means for limiting the turning movements of said roll holder in opposite directions, said limiting means comprising 10 intermeshing rotary devices.
20. In a typewriting machine and in carbon roll mechanism, the combination of printing devices, a rotary roll holder, means tending constantly to turn the same in one 15 direction, and stop devices for limiting the turning movement of said roll holder, one of said stop devices being movable step-by-step by the other stop devices to arresting position.
- 20 21. In a typewriting machine and in carbon roll mechanism, the combination of printing devices, a rotary roll holder, means tending constantly to turn the same in one direction, and toothed rotary stop devices 25 one of said devices turning the other step-by-step to arresting position.
22. In a typewriting machine and in carbon roll mechanism, the combination of printing devices, a rotary roll holder, means 30 tending constantly to turn the same in one direction, a rotary stop provided with a plurality of teeth in addition to a single locking tooth, and a co-acting stop connected to said roll holder and operative to turn said 35 first named stop until the locking tooth thereon is reached.
23. In a typewriting machine and in carbon roll mechanism, the combination of printing devices, a rotary roll holder, means 40 tending constantly to turn the same in one direction, a rotary stop provided with a plurality of teeth in addition to a single locking tooth, and two rotary stops provided with co-acting locking teeth, one of said 45 stops being further provided with additional teeth through which said stop may be turned step-by-step by the other stop.
24. In a typewriting machine and in carbon roll mechanism, the combination of 50 printing devices, a rotary roll holder comprising a tubular core and end flanges, a fixed shaft for said roll holder, a coiled spring connecting said shaft with said core, a stop rigid with said roll holder, and a sec- 55 ond stop mounted independently of said roll

holder and movable by said first named stop to arresting position.

25. In a typewriting machine and in carbon roll mechanism, the combination of printing devices, a support on the platen 60 carrier, an upright shaft rigid on said support, an upright roll holder rotatable on said shaft, a spring within said roll holder and connecting the same to said shaft, the upper flange of said roll holder being detachable, and a thumb screw providing an upper support for said roll holder, said thumb screw being removable to permit the removal of the upper flange of said roll holder and also to give access to said shaft 65 so that the setting of the same may be varied to adjust the tension of said spring.

26. In a typewriting machine and in carbon roll mechanism, the combination with the typewriter carriage of a supporting 75 frame detachably secured to said carriage, a pair of upright roll holders secured one at each side of said frame, and oppositely inclined guiding devices on said frame for changing the direction of the carbon paper and for 80 guiding superposed work sheets to the platen.

27. In a typewriting machine and carbon roll mechanism, the combination with a typewriter carriage of a supporting frame detachably secured to said carriage, a pair 85 of upright roll holders secured one at each end of said frame, and oppositely inclined triangular guiding devices secured to said frame between said roll holders.

28. In a typewriting machine and in carbon roll mechanism, the combination of a supporting frame detachably secured to the frame of the machine and comprising upright side plates and horizontal connecting tie rods, upright carbon roll carriers vertically supported on brackets outside the side plates, the latter being slotted to permit the carbon paper to pass inward from the roll, triangular guiding devices having inclined turning bars, said devices being secured to 95 the side plates and overlying one another, and a paper severing device also mounted on said supporting frame.

Signed at Syracuse, in the county of Onondaga, and State of New York this 24th 105 day of October, A. D. 1911.

HERBERT H. STEELE.
